ATTORNEYS.

UNITED STATES PATENT OFFICE.

WILLIAM A. REILLY, OF WYOMING, PENNSYLVANIA.

COAL JIG.

Application filed April 29, 1924. Serial No. 709,733.

My invention relates to coal jigs and similar apparatus employed for the washing and separation of coal, ore and the like from foreign matter which it is desired to eliminate.

The general object of the invention is to provide a novel construction of apparatus comprising means whereby the finer or smaller sizes of coal are prevented from becoming intermingled with the slate in the tank and thereby lost.

A further object of the invention is to provide an apparatus of the character indicated comprising means whereby a more complete and efficient separation of the coal from the slate and other foreign matter of greater specific gravity than the coal may be effected.

A further and more specific object of the invention is to provide means whereby the coal from the jig pan is adapted to be delivered into the tank so that a portion thereof, particularly the finer grades or sizes, settle in the bottom or boot of the tank where they may be removed by the usual endless conveyer, while the slate is delivered into a receptacle the bottom, sides and lower end of which are closed and from which the said slate is removed without being allowed to enter the tank as heretofore has been the practice.

To these and other ends the invention comprehends the novel construction and arrangement of parts as hereinafter described, particularly pointed out in the claims and as illustrated in the accompanying drawing in which I have illustrated one convenient form of mechanical embodiment of the said invention.

However, it will be understood that the invention is susceptible of embodiment in other forms of construction than that shown and that changes in the details of construction may be made within the scope of the claims without departing from the said invention.

In the drawing:

Fig. 1 is a longitudinal vertical sectional view of a coal jig embodying the invention; Fig. 2 is a transverse sectional view taken on the line 2—2 of Fig. 1; and

Fig. 3 is a top plan view of a portion of the said jig.

Referring to the drawing: 1 designates as a whole a frame structure within which and

supported thereby is a tank 2 of usual construction. The front and rear walls of the said tank are convergent so that any material discharged thereinto is concentrated at the lower end thereof in a boot or pocket 60 2^a open at its lower end as shown, which opening is adapted to be closed by a slideable door or valve 3 which is adapted to be actuated by the rod 4 and pivoted handle 5. Mounted within the tank 2 is a jig pan 10 65 the opposite sides of which are secured to bars 11 the lower ends of which are reduced and extend through openings in horizontal flanges upon brackets 12. The upper ends of the bars 11 are mounted upon eccentrics 70 15 upon a shaft 16 which is adapted to be rotated by a driving band (not shown) which engages the wheel pulleys 17 one of which is fast and the other loose thereon. The opposite end of the shaft 16 is provided with 75 a drive wheel 18 which is engaged by a drive belt 20 which belt also engages a wheel 21 upon a shaft 22 provided with drums or pulleys 25 (one only of which is shown) by means of which the coal and slate conveyors 27 and 28 are driven. The lower ends of the said conveyors 27 and 28 engage and travel over drums or pulleys 29 and 30, the latter being indicated in dotted lines in Fig. 1 of the drawing. 80

The conveyer 27 is located in a run-way of rectangular shape in cross-section formed by a portion of the bottom of the tank 2, a side thereof and the partition plate 27^a. The lower end of the said run-way is open 90 and the lower end of the said conveyer extends into the tank and terminates within the pocket 2^a at a point directly above the opening therein which is closed by the slideable door or valve 3. 95

The slate conveyer 28 is mounted in an upwardly and rearwardly inclined run-way or pocket formed by a portion of the bottom of the tank 2, the adjacent side of the tank, the partition 27^a previously referred to, and the closure for the lower end thereof. 100

The mixture of coal and slate is discharged as shown from a chute 35 into the front end portion of the jig pan 10 the bottom of which is perforated as shown. The said jig pan is provided with an adjustable baffle plate 36 under the lower edge of which the mixture of coal, slate and other impurities is caused to pass. As already indicated, the jig pan is vibrated by the rotation of the 110

eccentrics 15 previously referred to and the motion is such that the mixture of coal and slate is caused to move slowly forward toward the rear or discharge end of the jig 5 pan.

The coal is of less specific gravity than the slate and other impurities which may be present, in consequence of which certain of the coal, immediately after it has passed beyond the baffle plate 36, rises upwardly within the body of water within the jig pan 10, and in order that such coal may not have to travel forward to the discharge chute 40 at the rear end of the tank I have provided means whereby it may be discharged from points intermediate the opposite ends of the opposite sides of the jig pan 10. In order that the forward movement of the coal which separates from the slate immediately after the mixture of coal and slate has passed underneath the baffle plate 36 may be interrupted and caused to be discharged laterally from the jig pan I have provided an angle plate having one of its flanges 41 arranged in a substantially horizontal plane and extended toward the front end of the jig pan. The opposite flange 42 of the said angle plate extends in a vertical direction and the opposite ends of the said angle plate are secured in or adjacent rectangular notches or slots 45 formed in the opposite sides of the jig pan. The depth of the water in the jig pan is such that a considerable portion of the angle plate is submerged therein. The horizontal flange 41 of said plate occupies a position a substantial distance below the top of the water in the said jig pan. The result of this arrangement is that the coal which separates from the slate and rises in the water within the jig pan immediately after the mixture of coal and slate has passed from underneath the lower edge of the baffle plate 36 is caught by the angle plate and is guided by the same horizontally in lateral directions and is caused to be discharged through the notches or openings 45 into the tank 2. The coal so discharged settles to the bottom of the tank from which it is adapted to be removed by the conveyer 27. As the mixture of coal, slate and other impurities of greater specific gravity than the coal moves forward a further separation takes place and the coal, which is of less specific gravity than the foreign material, including the slate, rises to the top and is discharged through the chute 40 onto the conveyer 27 which is traveling in the direction indicated by the arrow in Fig. 1 of the drawing. Such of the coal as does not fall through the conveyer downwardly onto the bottom of the trough or run-way within which the conveyer is situated is carried downwardly to the bottom of the tank 2 and is intermingled with the coal which is discharged through the notches or openings 45

as previously described. An angular baffle plate 50 is provided for preventing any of the coal from entering the slate discharge trough or receptacle previously referred to.

The slate and other impurities of greater specific gravity than the coal are discharged underneath the lower edge of the breast plate 55. The discharge of the slate and other foreign matter of greater specific gravity than the coal is controlled by a door 56 which is hinged at 57 to the relatively stationary forward edge of the bottom of the jig pan 10. The said door is perforated and constitutes in effect a continuation of the bottom of the said pan. The said door is adapted to contact with the lower edge of the breast plate 55 along a line near its outer lower edge and is adapted to be held in contactual relation with respect to the lower edge of the said baffle plate by rods 58 the lower ends of which are connected to lugs or ears upon the rear edge of the said door or valve, while the upper ends thereof are connected with the rear ends of levers 59 which are pivoted intermediate their ends upon the upper ends of posts 60 which are secured at their lower ends to the opposite sides of the jig pan 10. The forwardly extending ends of the levers 59 are provided with adjustable weights 61.

Situated above the conveyer 27 and the run-way or trough within which it is situated and underneath a portion of the pivoted door or valve 56 is a cross-wise extending plate 65 which is inclined toward the conveyer 28 and the trough or receptacle within which it is situated so as to deliver the portion of the slate which is discharged above the conveyer 27 onto the conveyer 28. As a further means of preventing the slate from escaping into the tank 2 and intermingling with the coal therein I have provided the perforated inclined baffle plate 67 which extends upwardly and forwardly from the upper edge of the closure 32 and from the front edge of the plate 65.

It will be seen that by my invention I have provided a coal jig in which the coal is adapted to be discharged from the jig pan into the tank within which the jig pan is located and that in consequence thereof all of the grades or sizes of the coal, including the very finest which may be present, are concentrated in the reduced bottom portion of the tank from which they are removed by the conveyer provided for that purpose. The slate and other impurities of greater specific gravity than the coal are, contrary to the usual practice, delivered into a trough or chute from which they are removed by a conveyer and are not permitted to enter the tank.

It will also be noted that the efficiency of the jig is increased by providing means whereby certain of the coal which is first

separated from the slate and other impurities of greater specific gravity than the coal may be removed from the jig pan without the necessity of being moved or carried forward to the rear discharge end of the said pan.

Having thus described my invention, what I claim and desire to secure by Letters Patent is:

- 10 1. In a coal jig, the combination of a tank, a vibratable jig pan supported within the said tank, the opposite sides of said jig pan being provided with openings at their upper edges intermediate their opposite ends, an angular plate having its opposite ends mounted within said openings, a portion of the said plate occupying a substantially horizontal plane and extending toward the front of the said jig pan and another portion 20 thereof extending upwardly in a substantially vertical direction, the horizontal portion of the said plate being adapted to be submerged within the water in the said jig pan whereby the said plate is adapted to interrupt the rearward movement of coal which separates from the slate in the front part of the said jig pan, and the said jig pan being provided with coal and slate discharge means at its rear end, the coal being 25 adapted to be discharged into the said tank, a receptacle into which the said slate is to be discharged, and conveyers for removing

the said coal and slate from the coal jig, substantially as described.

2. In a coal jig, the combination of a 35 tank adapted to hold water, a vibratable jig pan mounted within said tank and partially submerged by the said water, means for delivering a mixture of coal and slate to the said jig pan, which jig pan is provided at 40 the upper edge of its rear end with coal discharge means and at the lower edge of its rear end with slate discharge means, a conveyer for removing the coal from the said tank, said conveyer extending to a point adjacent the bottom of the said tank, a conveyer for conveying the slate from the said jig pan, a receptacle within which the said last mentioned conveyer is situated, a transversely extending chute situated over the coal 45 conveyer and receiving a portion of the slate which is discharged from the said jig pan and conveying it into the said receptacle, the remainder of the said slate which is discharged from the said jig pan being delivered directly into the said receptacle, and the lower end of the said receptacle being 50 perforated, substantially as and for the purpose described.

In testimony that I claim the foregoing 55 as my invention I have hereunto signed my name this 15th day of April, A. D., 1924.

WILLIAM A. REILLY.
